DESIGN FOR A CONVEYER

Gerald C. Paxton, Riverside, Calif., assignor to
Food Machinery Corporation, San Jose, Calif.,
a corporation of Delaware

Application March 4, 1940, Serial No. 90,649

Term of patent 14 years

To all whom it may concern:

Be it known that I, Gerald C. Paxton, a citizen of the United States, residing at Riverside, in the county of Riverside and State of California, have invented a new, original, and ornamental Design for a Conveyer, of which the following is a specification, reference being had to the accompanying drawing, forming a part thereof.

Fig. 1 is a plan view of a conveyer embodying my new design.

Fig. 2 is an enlarged detail perspective view,

partially in cross section, illustrating the conveyer design at the turn illustrated in Fig. 1.

Fig. 3 is a detail perspective view, on substantially the same scale as Fig. 2, and illustrating an end of said conveyer illustrated in plan in Fig. 1.

I claim:

The ornamental design for a conveyer, as shown.

GERALD C. PAXTON.
